UNITED STATES PATENT OFFICE.

MARTHE R. LEMERCIER STROCKER, OF WASHINGTON, DISTRICT OF COLUMBIA.

BRASSIÈRE-CORSET.

1,312,459.

Specification of Letters Patent.

Patented Aug. 5, 1919.

Application filed July 27, 1917. Serial No. 183,161.

To all whom it may concern:

Be it known that I, MARTHE R. LEMERCIER STROCKER, a citizen of the United States, residing at Washington, in the District of Columbia, have invented certain new and useful improvements in Brassière-Corsets; and I do hereby declare the following to be a full, clear, and exact description of the invention, such as will enable others skilled in the art to which it appertains to make and use the same.

This invention relates to a combined brassière and corset and to the method of making the same.

One of the objects of the present invention is to set forth a process of making the garment whereby the corset and the brassière are cut integrally in the gores and the brassière is subsequently cut, or partly cut therefrom whereby the original gore and stay lines are preserved in the brassière.

Another object of the invention is to provide a corset and a brassière for the corset made in accordance with this process.

Another object of the present invention is to provide a corset and a bust support which eliminate the objectionable flesh ridge or break immediately above the top of the ordinary corset.

Another object of the invention is to provide a garment which will give a perfect fit and support and yet will readily yield to all movements of the wearer without undue pressure or restraint.

Another object of the invention is to provide a perfect support for the base of the shoulder blades; and to provide means to hold the upper edges of the stiffened body, at both front and back, close to the body of the wearer, thus preventing the ends of the stays from springing outwardly and showing through the outer garments, as is frequently the case with ordinary corsets, especially when the body is contorted.

Another aim of the invention is to provide a brassière having curved ribs positioned to conform to the natural bust line of the body.

Another feature of the invention resides in the yieldable connection between the corset and the brassière which permits the latter to follow the bust movement and which eliminates the objectionable sagging or riding of the brassière in relation to the bust.

Still another feature of the invention resides in having the stays adjacent the inner

edges of the back gores non-continuous, providing a break immediately at the waistline, such non-continuous stays being braced by the adjacent full length stays and also by the provision of a lacing eyelet or other fastening means immediately at the waist line or point of stay break to assist in the back support and to produce the impression and appearance of a longer waist line.

Another feature of the invention relates to the construction of the back of the corset, particularly in the relation of the waist lines on which the rear gores are cut.

These and other features of the invention will be hereinafter more specifically pointed out.

Referring to the accompanying drawings in which similar reference numerals indicate corresponding parts,

Figure 1 is a front elevation of the back-laced brassière corset made in accordance with my invention, the left side of the brassière thrown open to show the curved rib construction.

Fig. 2 is a rear elevation of the same.

Fig. 3 is a view showing the unboned gores of the corset laid out flat, the manner of cutting the brassière being illustrated.

Fig. 4 is a detailed view of the back showing the two rear gores from the waist line down cut parallel and the same from the waist line up, cut at an angle.

Fig. 5 is a detailed view of the corset showing the brassière made in the same manner but detachable from the corset proper.

Fig. 6 is a view of my improved corset provided with a front lace.

Fig. 7 is a rear view of the same showing a variation of the manner of constructing the back, and,

Fig. 8 is a detailed view of the mode of detachably connecting the corset and the brassière.

The corset may be constructed of any suitable material and of any number of sections or gores, depending upon the size and figure of the wearer. According to the present method, the front gores are cut to integrally include the bust portion of the figure. For instance, as shown in Fig. 3, the front gores 1 and 2 have the bust supporting portion 10 made from the same piece as the lower corset portion 11.

After the gores are sewed together and the corset fitted to the figure, the bust line

is determined. This latter may be that of the individual fitted or an average bust line, where the corsets are to be made in sizes. The front gores are now cut from the middle line 12 of the front gore along the bust line 13, to approximately the point 14, adjacent to the under arm seam. Only in case where it is desirable to have the brassière or bust support permanently attached to or made part of the corset as, for instance, in Figs. 1, 2 and 3, should this line of severance 13 terminate at approximately the point 14. If it be desirable to make the same detachable from the corset proper, the line of severance 13 of the brassière is made completely across all the bust supporting portions of those particular gores. For example, in Fig. 5 the cut 13 would be continued to completely sever gore 2.

Obviously, there may be more than two such front gores and it is also apparent that there is no necessity for terminating the severance 13 at the underseam 15 as the same may end at any point in front of or to the rear thereof. So also there is no necessity for positioning the seam 15 directly beneath the arm.

While the remaining steps in the process 30 of making my improved corset are those ordinarily used in the corset making art of the present day, it is to be understood that the corset itself embodies many novel features of construction which will now be recited.

Figs. 1 and 2 show a back-laced corset with an attached bust-piece or brassière made as above described. And as shown in these figures the gores 11 for the corset proper are provided with the usual bone or stay members 15 of any desirable material, terminating at the bust line 13 at the top of the corset and at any desirable point at the hips thereof. The brassière or bust support 45 16 which, as has been set forth, is formed by severing the same at the bust line from the gores which were originally cut and fitted to include this portion, is provided with ribs, bones, stays, or other members 17 which are given a curved formation to follow the natural line of the bust and preferably the line of the human ribs. At the front the brassière is provided with any type of fastening means such as the hook and eye and ribbon illustrated in Fig. 1.

Attached to, or detachably fastened to one of the lower portions of the brassière, is an elastic member 18. The other end of which is in like manner connected with the 60 corset proper as at 19, so that the brassière is held in over-lapping relation to the top of the corset and yet is permitted to flexibly adjust itself to the movements of the wearer. And this adjusting movement is aided by 65 means of shoulder straps or bands 23, pref-

erably elastic, which are connected either detachably or permanently to the preferably pointed part 22 of the bust portion of the front, and similarly in the rear, to the shoulder portions 24.

It will be seen that such a construction permits the brassière to hug the breast without undue pressure or restraint and at the same time allow the brassière to freely follow the natural movements of the bust, 75 and the shoulder straps 23 together with the elastic 18, hold the upper edges of the brassière and corset, both at the front and back close to the body of the wearer and thus prevent the ends of the stays from 80 springing outwardly and presenting an unsightly appearance. Furthermore the rear shoulder flaps 24, provide a most perfect support for the shoulder blades which tend to project in some figures. The curved ribs 85 17 of the brassière give and maintain the graceful curved lines of the bust.

For the purpose of assuring a more correct lacing of the corset, and for securing a natural V-shape between the immediate 90 back gores from the waist line upwardly in the back the inside lines of the immediate back gores 4 are cut as illustrated in Fig. 4. As there shown, from the waist line 26 downwardly, these inside gore lines run 95 parallel but from the waist line upwardly to the top of the waist, these back gore inside lines are cut at an angle as indicated at 27, so that when the wearer laces herself or is laced, there will be a tendency for the 100 back to assume a natural V-opening at the upper laced portion, and the tendency for the lacer to force the upper inside edges of the back of the corset together is diminished. The inverted V-shape of the lower laced 105 portion is taken care of by the natural shape of the hips.

Furthermore, in order to eliminate the constant pressure, rubbing and feverish condition produced by the usual rigid, continuous stay members at the back, the inside bone or stay members of the back gores 4 are ended or broken at the waist line as at 28. But in order to provide sufficient rigidity and give a continuous support for the 110 corset the ribs adjacent these non-continuous ribs are made to continue across the waist line as at 15 and extend preferably the usual length of the corset. It will be noticed that a lacing eyelet or other fastening member 31 is positioned immediately at the waist line 26 or at the break 28 of the stay member and this provides an additional support at the back and gives the wearer the impression of a longer waist line.

A corset having a detachable brassière and made as hereinbefore set forth is illustrated in detail in Fig. 5 which shows the front gores 1 and 2 and the line of severance 13, extending entirely across gore 2 and termi- 130

nating at gore 3. In order to lace or otherwise detachably fasten the brassière or bust piece to corset, the former is provided with the usual eyelets 31 located between the ribs 5 15 thereof. The corset is likewise provided with eyelets 32 or other fastening means positioned adjacent the stay 15.

To assist in holding the brassière in position and yet allow flexibility of movement 10 thereof the corset proper is provided with an eyelet or fastening member 33 located below the line of severance 13 or in any convenient position so that the bottom of the brassière may be fastened to the corset. In 15 this manner the bust piece is firmly held on the top of corset.

Figs. 7 and 8 illustrate the manner in which my invention may be applied to a front laced corset. In the back, instead of 20 having a continuous lace, as illustrated in Fig. 2, there is provided from the waist line to the bottom of the corset, a gusset 35 of rubberized fabric, which provides a flexible 25 adjustment for the hips, while the upper laced portion permits any adjustment to be made in the back portion of the corset, which once adjusted to the form of the back of the wearer remains permanent as the size 30 of the corset is controlled by the lacing in the front.

The front laced corset may have the brassière attached or detached therefrom, the latter construction being shown in Fig. 8.

It is obvious that the curved ribs 17 of 35 the bust portion of the corset, which are curved to the natural bust of the wearer or to an average bust when the corsets are made in sizes, and which ribs preferably extend diagonally of the brassière from the upper 40 and front edges thereof to the lower, and curve toward the underarm of the corset. These ribs which are preferably small and 45 yieldable are also given a slight bow or outward bulge to maintain the graceful lines of the bust and to assist in holding the same. And while it is within the contemplation of this invention to arrange the curved ribs to extend diagonally in any direction or curved transversely of the brassière, the present 50 arrangement produces the most pleasing lines and most effectively aids in supporting the bust. This rib construction may be applied to any type of bust support or brassière whether a separate garment or used in 55 connection with my improved corset.

It is clear that the present invention is adapted to any type of corset whether low, medium or high top.

Claims:

- 60 1. The process of making a brassière-corset consisting in cutting the brassière and corset in integral gores, cutting the bust including gores along the bust line to form a brassière.
- 65 2. The process of making a brassière-cor-

set consisting in cutting the brassière and corset proper in integral gores, cutting certain of the gores along the bust line from the front gores to points substantially at the underarm seam of the corset. 70

3. The process of making a brassière-corset comprising cutting some of the corset gores to integrally include bust supporting portions, cutting those gores which include bust supporting portions along the bust line 75 from the front gores backward toward the back of the corset, whereby to form a brassière for the corset.

4. The process of making a brassière-corset comprising cutting some of the corset 80 gores to integrally include bust supporting portions, cutting those gores which include bust supporting portions along the bust line to sever the bust portions therefrom, finishing the bust supporting portion and the 85 corset proper, and providing the corset proper with means whereby the bust portion may be attached thereto.

5. In a brassière corset the combination of 90 a corset portion having front gores terminating at the bust line, a brassière adapted to be attached thereto substantially at the under-arm seam of said corset, said brassière comprising bust supporting gores terminating at the bust line, each of which 95 forms with its respective corset gore a continuous form fitting gore, said brassière being also resiliently attached to said corset at the front bust line portion.

6. In a brassière corset the combination 100 of a corset portion including a plurality of front gores terminating at the bust line, a brassière therefor comprising a plurality of gores terminating at the bust line and each forming a continuation of its respective corset gore, a shoulder strap connecting the brassière and corset back and resilient means connecting the lowermost front portion of said brassière to said corset whereby said brassière is held flexibly in bust supporting position. 105

7. A corset brassière terminating at the bust line and projecting upwardly over the bust, a plurality of curved ribs extending from the bust line thereof diagonally upward to support the bust and preserve the 110 natural contour thereof.

8. A corset having spaced stays on the back gores thereof, the stays at and adjacent the inner edges of the back gores terminating at the waist line thereof, lacing means between said stays, one of such means being directly at the waist line. 120

9. The combination of a front laced corset, the inner edges of the back gores of 125 said corset being joined by a permanent gusset of elastic fabric from the waist line downward and adjustable lacing means for said edges from the waist line upward.

10. A corset having the adjacent inner 130

edges of its back gores cut parallel from the waist line to the bottom of the corset and cut at an angle from the waist line to the top of the corset.

5 11. In a brassière corset, the combination of a corset portion the front gores of which terminate at the bust line, a brassière composed of bust supporting gores terminating at the bust line, each of which forms with 10 its respective corset gore a continuous form fitting gore.

12. A corset having the adjacent inner edges of its back gores cut parallel from the waist line to bottom of the corset and cut 15 at an angle from the waist line to the top of the corset to provide a substantially V

shaped space between the upper portion of said edges, spaced stays on the back gore, the stays adjacent the inner edges of said gores terminating at the waist line, lacing 20 means between said stays, one of such means being directly at the waist line whereby the break at the waist line is braced and said V shaped space between the edges of the back gores is preserved.

In testimony whereof I affix my signature in the presence of two witnesses.
